DRIVING MECHANISM FOR ROTARY BRAIDERS

**Fred Autem, Wyomissing, Pa., assignor to Textile
Machine Works, Wyomissing, Pa., a corporation
of Pennsylvania**

Application March 2, 1932, Serial No. 596,181

4 Claims. (Cl. 96—7)

My invention relates to rotary braiding machines and particularly to a device which is adapted to maintain continuous operating connections between a driving shaft and the carriers for one set of bobbins as they pass over threads from bobbins of another set and which is operable to cause said carriers to traverse said threads without contact between said connecting device and said threads.

10. In the drawings:

Figure 1 is a plan view, partly broken away, showing bobbin carriers in a braiding machine embodying the invention.

15. Figure 2 is a sectional view on the line 2—2 of Figure 1 illustrating a connecting device according to my invention for one of the bobbin carriers; and

Figure 3 is a sectional elevation, taken substantially along the line 3—3 of Fig. 1, with certain parts omitted, of a portion of the braiding machine.

In the drawings the numeral 10 designates a platform rotatably mounted on a hollow standard 11 and carrying a plurality of brackets 12 each of which supports one of the bobbins 13 of the lower set. Suitable gearing, not shown, is provided for effecting rotation of a member 21 about standard 11 in the same direction as platform 10 and in unison therewith.

30. The bobbins 22 of the upper set are mounted on individual carriers 23 each having a guide rib 24 engaging a circumferential groove 25 in a vertical flange 26 on member 21 and a fibre contact block 27 provided with a groove 28 engaging

35. a guide rib 30 on an inwardly extending annular flange 31 near the upper end of flange 26. Contact blocks 27 bear against anti-friction rollers 32 which are mounted on flange 31 and serve as a raceway for the carriers. Flange 31 is cut

40. away at a plurality of circumferentially spaced points in alignment with slots 33 provided in the flange 26 for receiving threads from the lower bobbins as carriers 23 for the upper bobbins 22 pass thereover.

45 The carriers 23 are driven on their raceway from a shaft 34 extending through standard 11 and carrying a plate 35 supporting brackets 36 on which are mounted rotatable fliers 37 operable to maintain a continuous driving connection
50 between shaft 34 and carriers 23 while at the same time permitting the carriers to pass over the threads from the lower bobbins without severing them.

55 Each flier 37 comprises a sleeve 38 having a pair of diametrically positioned lugs or wings

adjacent each end, the pair of lugs 40 at one end of sleeve 38 being angularly disposed with respect to the lugs 41 adjacent the other end thereof. The underside of contact block 27 is provided with spaced notches 42 and 43 for receiving a lug 40 or 41, respectively, to operatively connect the carrier 23 to shaft 34. Contact block 27 is provided with a rounded thread guiding edge 39 for preventing threads from the lower bobbins being caught in the slots 42 and 43. 60 65

Sleeve 38 is rotatably carried on a stud 49 mounted in a lug 44 on bracket 36 and is provided with a bevel gear 45. In the arrangement shown the construction is simplified by providing a single bracket 36 for each pair of carrier driving fliers 37 and their bevel gears 45 engage a single bevel gear 46. Bevel gear 46 is rotatable on a stud 47 on bracket 36 and is fixed to a pinion 48 which meshes with a gear ring 50 secured to and movable with member 21 for turning the fliers 37. As shown in Figs. 1 and 2, the stud 47 also journals one end of each of the studs 49 for the pair of sleeves 38 carried by bracket 36.

The threads 51 from the lower bobbins extend around suitable tensioning devices 52 and through a sinuous braiding channel 53 between the adjacent edges of a pair of fixed cylindrical plates 54, one of which is mounted on a non-rotatable spider 17 mounted on standard 11. As the platform 10 and member 21 are rotated relatively to plates 54 the sinuous channel 53 causes each thread to be alternately raised from and deposited in the corresponding slot 33 in member 21 to pass alternately over and under one or more of the bobbins 22 to the braiding point. Platform 10 and shaft 34 are driven in opposite directions by suitable driving means (not shown) so that shaft 34 is operated to rotate the carriers 23 for bobbins 22 on their raceway about the braiding point in the opposite direction to the movement of the lower bobbins and the raceway member 21. As a carrier 23 for an upper bobbin 22 passes over a slot 33 in the flange 26 of member 21 the rotation of the associated flier 37 causes a driving lug 40 to be rotated out of engagement with the notch 42 in block 27 so that in the event a thread 51 lies in the slot 33 so as to extend under the carrier 23 to the braiding point it will not be contacted by the lug 40. At the same time a lug 41 at the other end of the flier sleeve is rotated into the notch 43 for maintaining the driving connection between the shaft 34 and the carrier 23, it being understood that the depth of notches 42 and 43 is such that lug 40 does

not become fully disengaged until a lug 41 is in driving engagement with carrier 23.

As shown in the drawings, the peripheral length of the engaging end of a lug 40, 41 is desirably not substantially greater, and preferably less, than the length of the notches 42, 43 so that a particular lug engages in the corresponding notch for only a small part of a revolution of the fier. As a result, friction due to the faces of the lugs 10 rotating in contact with the walls of the notches is reduced. Further, because of the short intervals of engagement of the lugs it is not necessary to effect a fine adjustment in the initial positions of the lugs relatively to the carrier notches to 15 maintain proper timing with respect to other machine parts in order to properly provide for passage of the lower bobbin threads; the short peripheral extent of the lugs permitting considerable latitude to provide ample clearance for 20 thread passage in the interval between engagements of lugs corresponding in axial disposition on the fier.

While the peripheral extent of the engaging end of the fier lugs is preferably considerably less than the length of the carrier notch or slot, as shown, whereby it is possible to provide a plurality of lugs in each axial position, it might approach or slightly exceed the slot length. However, in order to maintain ample clearance for 25 passage of lower bobbin threads it is necessary that the gaps between the lugs should not be undesirably small and, therefore, the peripheral extent of the lugs should not be substantially greater than their radial length.

The provision of a plurality of lugs at each axial position permits the passage of several lower bobbin threads at each revolution of the fier rather than a single thread as in certain prior constructions. As a result, the rate of operation of the fier to maintain a continuous 30 driving connection may be reduced with a consequent reduction of friction and wear. The arrangement also permits the braider to be operated at a more rapid rate and such increase of 35 speed results in greater production.

As carrier 23 progresses over slot 33 the rotation of the fier 37 moves the lug 41 from driving relation in slot 43 so that it does not sever the thread 51, and the other lug 40 at the opposite 40 end of the fier sleeve enters the notch 42 to drive the carrier.

It is to be noted that each upper bobbin carrier is continuously and uninterruptedly connected to the driving shaft therefor by its fier inasmuch as a lug at one or the other end of the fier sleeve is positioned in the corresponding notch of the carrier block when a lug at the opposite end of the fier is rotated out of the corresponding notch to avoid contact with threads from the lower 50 bobbins.

What I claim is:

1. In a braiding machine having bobbin carrier structure, driving means therefor comprising rotatable fier structure having a plurality of carrier engaging members arranged in pairs spaced axially along said fier structure, the members of each pair being diametrically disposed with respect to their axis and relatively narrow in width to provide large oppositely disposed openings between the sides of the members, said

pairs of members being angularly disposed about said fier structure so that the members are successively engaged with and disengaged from said carrier structure to maintain a continuous driving connection between the carrier and fier structures while enabling a thread to pass therebetween, and means for maintaining a continuous driving connection with said fier structure for rotating the same. 80

2. In a braiding machine having bobbin carrier structure, driving means therefor comprising rotatable fier structure having a plurality of carrier engaging members arranged in pairs spaced axially along said fier structure, the members of each pair being diametrically disposed with respect to their axis and of such width that the angle of each of the two openings formed by the sides of the members of each pair is of the order of 180°, said pairs of members being angularly disposed about said fier structure so that the members are successively engaged with and disengaged from said carrier structure to maintain a continuous driving connection between the carrier and fier structures while enabling a thread to pass therebetween, and means for maintaining a continuous driving connection with said fier structure for rotating the same. 85

3. In a braiding machine having bobbin carrier structure with a plurality of slots therein, driving means therefor comprising rotatable fier structure having a plurality of relatively narrow lugs arranged in pairs spaced axially along said fier structure, the lugs of each pair being diametrically disposed with respect to their axis to provide large oppositely disposed openings between the lugs, said pairs of lugs being angularly disposed approximately 90° apart around said fier structure so that the lugs are successively engaged with and disengaged from their respective slots in said carrier structure to maintain a continuous driving connection between the carrier and fier structures while enabling a thread to pass therebetween, and means for maintaining a continuous driving connection with said fier structure for rotating the same. 100

4. In a braiding machine having bobbin carrier structure with a plurality of slots therein, driving means therefor comprising rotatable fier structure having a plurality of relatively narrow carrier engaging members arranged in groups of two only, said groups being spaced axially along the fier structure and adapted to engage in said slots in the bobbin carrier structure, the two members of each group extending in opposite directions and substantially along a straight line 110 passing through the axis of the fier structure thereby to provide large oppositely disposed openings between said members, the members of the said groups being angularly disposed about said fier structure so that the members are successively engaged with and disengaged from their respective slots in the carrier structure to maintain a continuous driving connection between the carrier and fier structures while enabling a thread to pass therebetween, and means for maintaining a continuous driving connection with said fier structure for rotating the same. 115
